UNITED STATES PATENT OFFICE

1,967,645

PRIMER VALVE

David S. Williams, Portland, Oreg.

Original application December 30, 1933, Serial
No. 704,637. Divided and this application
March 9, 1934, Serial No. 714,805

8 Claims. (Cl. 182—12)

This invention relates in general to improvements in valves, and particularly to primer valves which are adapted for automatic actuation by water pressure that normally is contained in a water supply line but which utilizes somewhat different mechanical principles from those set forth in my co-pending application for improvements in "Primer valves," Serial No. 704,637 filed December 30, 1933, out of which this application 10 has been divided to comply with rule 41 of the rules of practice in the United States Patent Office, and from those set forth in my co-pending divisional application for improvements in "Primer valves," Serial No. 714,210, filed March 6, 1934.

15 The subject matter of this application is capable of fulfilling all of the objects set forth in the above-identified co-pending applications insofar as the subject matter common to the three is concerned, and, while the device illustrated as 20 embodying the present invention is particularly designed for use with water traps of the well-known type, still it may have a wide and varied range of utility in other arts where it is essential to automatically actuate a valve by water 25 pressure.

My invention contemplates the provision of a primer valve which may be automatically actuated so that a water seal is at all times maintained in floor drain traps, sumps or other analogous contrivances so that the obnoxious gases usually generated in sewers and other disposal units cannot enter into houses or buildings from such sewers or other disposal units.

An important object of my invention is to provide a valve which, when installed directly or indirectly in a water supply line running to or from any service connection, will automatically maintain a predetermined amount of water as a seal against escaping obnoxious gases and/or will compensate for water losses in devices connected thereto due to use, evaporation, leakage or other causes.

An equally important object of my invention is to provide means for preventing foul water and air being siphoned from any drains into the water supply line.

An equally important object of my invention is to provide means for automatically bypassing a liquid flowing through a standard water supply line into a container which must either be sealed or which may in turn actuate other mechanism such as a fire alarm connected to a sprinkling system.

A still further object of my invention is to 55 provide a simple, practical, inexpensive and effi-

cient primer valve which may be manufactured at low cost and within a minimum of time.

The invention is directed to other objects and possesses other features of novelty and advantage and consists in the new and useful formation, 60 construction, combination and interrelation of parts, members and features, all of which will be more apparent from the following detailed description, having reference to the accompanying drawing which illustrates one embodiment by 65 which the invention may be realized and in which:

Figure 1 is a sectional, side view of the illustrated embodiment of my invention, including the construction of the inspection-unit, showing the position of the valve when the liquid in 70 the supply-line is at rest.

Figure 2 is a sectional, side view of the illustrated embodiment of the invention in Figure 1, showing the position of the valve when the liquid in the supply-line is in motion.

Figure 3 illustrates a water supply-line to which a standard type of faucet is attached and also to which a primer valve embodying my invention is directly connected and also indicating the manner of connecting the valve-unit to a 80 water-trap.

Figure 4 illustrates a water supply-line to which a primer valve embodying my invention is indirectly connected and indicating the manner for delivering a liquid to a station located at a 85 remote point from the main supply-line.

Figure 5 illustrates the application of a valve embodying my invention to a fire-alarm system operated by water flowing through a water supply-line.

Corresponding and like parts are referred to in the following description and indicated in all the views of the drawing by the same reference characters.

The invention may be incorporated in a structure as disclosed in the drawing, wherein the primer valve is generally designated by reference character A. The valve-body or casing 1 has an internal threaded boss 2 extending outwardly from one of its sides and an external threaded 100 boss 3 extends outwardly from the opposite side of and in direct alignment with boss 2. A wall or diaphragm 4 is disposed between bosses 2 and 3 and has opening 5 formed therein, the circumference of which is less than the circumference 105 of the passageway formed between bosses 2 and 3. The passageway is thus divided into chambers 6 and 7 by the wall or diaphragm 4. A port 8 is disposed through the lower portion of the wall or diaphragm 4, which assists in more ef- 110

ffectively equalizing the pressure between chambers 6 and 7, when the water in the supply-line reaches a state of rest.

Internal threaded wall 9 extends upwardly from the valve-member 1 and forms chamber 10 therebetween. Head cap 11 is threadably secured to the wall 9. A shaft 12 is secured to the wall 9 and a bell-crank 13 is journaled upon said shaft. The bell-crank 13 has arms 14 and 15. A weighted disc 16, the circumference of which is substantially equal to the circumference of the opening 5 in the diaphragm, is secured to or made integral with arm 14 of the bell-crank. A threaded-member 17 extends outwardly from arm 15 of the bell-crank, and a valve-cap 18 is threadably disposed upon the threaded-member 17. A valve-washer 19 made of any suitable material, such as rubber, is removably disposed within the valve-cap 18. The function of the bell-crank valve-assembly heretofore described will be related forthwith.

External threaded boss 20 extends outwardly from the wall 9. A hollow supply-tube 21 is removably disposed within the bore or passageway 22 formed within the boss 20, and said supply-tube extends a slight distance into the chamber 10. This supply-tube has a dome 23 formed at one end and an unrestricted opening formed at the other end. A flange 24 is disposed immediately adjacent the unrestricted opening of the supply-tube 21, and a restricted opening or port 25 is disposed through the apex of the dome 23. The flange 24 is adapted to fit snugly against the end 26 of the boss 20, and the supply-tube 21 is positioned within the passageway 22 so that the restricted opening or port 25 may be normally sealed by the valve-washer 19.

The bell-crank valve-assembly hereinabove described is constructed so that the valve-washer is in direct alignment with the opening or port 25, and it is within the contemplation of the invention that the washer should normally remain seated and maintain the opening 25 under seal. In order to effect this desirable end, the bell-crank valve-assembly is constructed so that the side 27 of the weighted disc 16 does not come in contact with the side 28 of the diaphragm 4, and, for all practical purposes, remains in position for pendulum action and covers the opening 5 sufficiently to rock the bell-crank valve-assembly when the water within the supply-line is put into motion. From the above detailed description it at once becomes apparent that the supply-tube 21 is normally maintained out of communication with the chamber 10. It is only when the motion of the water under pressure in the supply-line swings the bell-crank valve-assembly on shaft 12 that the port 25 is unsealed permitting some of the water to be by-passed into the supply-tube 21. This action is graphically illustrated in Figure 2.

A union-connection 29 has a bore or passageway 30 therethrough. A flange 31 is formed at one end of the union-connection, and an internal threaded boss 32 is formed at the other end thereof. The flange 31 is adapted to intimately fit against the flange 24 of the supply-tube 21. These flanges are held in intimate engagement with each other by union-coupling 33 that is threadably disposed on boss 20. An air-vent opening 34 extends upwardly from the union-connection 29, and a slip-cap 35 is disposed thereon so that a portion thereof is in spaced relationship to the vent-opening in order to form an air-vent as shown at 36. Attention

might well be called to the fact that the vent assembly fulfills several important functions. Not only does the vent assembly permit inspection and supply air to the supply tube, but it also eliminates the possibility of a siphon action taking place between the supply tube and the drain to which the vent assembly is connected. Thus the possibility of foul water and air in the drains being siphoned into the water supply line and contaminating the water therein is entirely prevented.

Figure 3 illustrates one of the valves embodying the invention heretofore described, which is directly connected to a water supply-line. Boss 2 has threaded therein conduit 37, which comes from a source of water supply not shown, and conduit 38 is joined to boss 3 by union-coupling 39. A faucet 40 is shown connected to conduit 38. However, any other service connection may be effected without changing the operation of the primer valve. The vent-assembly may be joined to drain-trap 41, or to any other contrivance which requires a supply of water, through any desirable means, as through conduit 42 being threaded in boss 32.

In Figure 4 is illustrated a valve identical in structure with the valve illustrated in Figure 3. However, this valve is shown indirectly connected with a water supply-line. The main water supply passes through conduit 43. Water is bypassed into the valve through conduit 44, which is threaded into boss 2. The by-passed water that does not enter the vent-assembly is returned to the main water supply line through conduit 45, which is engaged with threaded boss 3 through union-coupling 46. The water entering the vent-assembly may be directed to any device which requires a supply of water either for purposes of effecting a water seal or for any other purpose. This particular arrangement does not in any way affect the operation of the valve constructed in accordance with the invention.

In Figure 5 there is illustrated a further use for the invention. This illustration shows a valve identical in all material particulars with the valve shown in Figures 3 and 4. However, some simple modifications have been made thereto in order to permit its use as a control for a fire alarm system operated by water moving in a water supply line. The shaft 12 is made to extend outwardly as shown at 47, so that an arm 48 may be made integral therewith or removably secured thereto. This arm may be connected to tripping means for making an electrical connection or the arm may be connected in any other manner provided that the connection produces the results desired, namely, the setting off of an alarm when water actuates the bell crank valve assembly. A packing gland 49 surrounds the exposed portion of the shaft 12, thereby effecting a water tight connection without hindering the movement of the shaft and an oil retaining member 50 surrounds the packing gland in order to prevent corrosion and also for the purpose of lubricating the shaft.

Modus operandi

Having fully described the details of the invention, it is well to indicate the manner of its operation. When a service outlet is open, the water within the supply-line being under pressure, is forced to surge toward the valve-assembly causing the weighted arm of the bell-crank-valve-assembly to be swung away from opening 5. This action simultaneously removes

the valve-cap from port 25, permitting the water to enter into the supply-tube 21 and from there the water enters into the vent-assembly from where it travels to any device requiring water 5 for sealing purposes or for any other purpose.

The relative position of the bell-crank-valve-assembly, when the water is in motion within the valve-body, is graphically illustrated in Figure 2, and the position of the same valve when 10 the water is at rest is graphically illustrated in Figure 1.

The invention has been described in connection with a specific illustrative embodiment disclosing a definite arrangement of parts. However, it will be understood that a wide range 15 of variants thereof is possible to those skilled in the art without departing from the broad spirit of the invention, since the invention, in its broader aspect, is not limited to the specific 20 construction herein described and shown, as changes in the size, proportions, arrangements and mechanical relations as well as additions, omissions and substitutions in the form or parts 25 may be made which fall within the scope of the subject matter incorporated in the appended claims.

Having thus disclosed my invention, what I claim as new and upon which I desire to secure Letters Patent is:

30 1. In a device of the class described, a body-member having a bore therethrough, a diaphragm disposed within and dividing said bore into two chambers, said diaphragm having an opening therethrough, the circumference of which is materially less than the circumference of the interior of the bore, means rockably disposed within the body-member and normally covering the opening in the diaphragm responsive to the pressure of water passing through the bore of the 35 body-member, and a supply tube removably disposed within the body-member in parallel offset with the bore of said body-member, said supply tube having a restricted opening through one end thereof in direct alignment with a portion of said 40 rockable means, said portion normally sealing said opening when said means normally covers the opening within the diaphragm.

2. In a device of the class described, a body-member having a bore therethrough, a diaphragm disposed within and dividing said bore into two chambers, said diaphragm having an opening therethrough, means rockably disposed within the body-member and normally covering the opening in the diaphragm responsive to the pressure of water passing through the bore of the 50 body-member, a hollow-stem removably disposed within the body-member in direct alignment with a portion of said means, said hollow-stem having an opening therein adapted to be sealed by 55 said means when said means normally covers the opening within the diaphragm, and a vent-unit 60 removably secured to and in direct alignment with the hollow-stem.

3. A device characterized as in claim 2, wherein in the vent-unit consists of a conduit in registerable alignment with the hollow-stem, a vent-opening disposed through said conduit, and a slip-cap-protector covering said vent. 80

4. A device characterized as in claim 2, wherein in the rockable means consists of a bell-crank valve-assembly movably journaled within said body-member, said bell-crank assembly having a weighted disc secured to one arm thereof positioned in direct alignment with the opening in the diaphragm and having a valve-cap assembly secured to the other arm thereof positioned in direct alignment with and normally sealing the opening in the hollow-stem. 85

5. In combination with a source of water supply under pressure, a primer valve comprising a body-member having a bore therethrough, a diaphragm dividing said bore, said diaphragm having an opening therein, a hollow-stem removably disposed within the body-member and in spaced relationship with said bore, said hollow-stem having an opening through one end thereof, a shaft journaled within said body-member, and a bell-crank valve-assembly movably journaled about 90 said shaft, one end of said bell-crank valve-assembly adapted to normally cover the opening in the diaphragm and the other end of said bell-crank valve-assembly adapted to seal normally the opening in the hollow-stem, said bell-crank valve-assembly being adapted to rockably respond to water under pressure to thereby uncover said openings. 100

6. A device characterized as in claim 5, including a vent-unit disposed in registerable 110 alignment with said hollow-stem.

7. A primer valve comprising a body member having an inlet passageway, an outlet passageway and a chamber formed therein, a diaphragm having an opening therein disposed between the 115 inlet passageway and the outlet passageway, a hollow-stem disposed within the body member in parallel offset with the inlet and outlet passageways and having its free end extending within said chamber, said hollow-stem having an opening 120 therein at its free end, a shaft journaled within said chamber, a bell-crank valve assembly movably journaled about said shaft comprising a weighted disc secured to one end of said bell-crank and being in direct alignment with 125 the opening in the diaphragm, and a valve-cap secured to the other end of the bell-crank, said valve-cap being in direct alignment and normally in intimate contact with the opening in said hollow-stem, said bell-crank assembly being 130 adapted to be rocked by water under pressure. 135

8. Apparatus as characterized in claim 7, including a conduit in registerable alignment with the hollow-stem, a vent-opening disposed through said conduit, and a slip-cap protector covering said vent. 140

DAVID S. WILLIAMS.
